COMBUSTION REGULATOR

Guido Wünsch, Berlin-Steglitz, Germany, and
Herbert Ziebolz, Chicago, Ill., assignors to As-
kania-Werke A. G. vormals Central Werkstatt
Dessau und Carl Bamberg-Friedenau, a Ger-
man company

Application July 12, 1932, Serial No. 622,168

2 Claims. (Cl. 236—15)

This invention relates to regulating apparatus for controlling combustion in furnaces and the like and, among other objects, aims to provide improved regulating mechanism which is operated in accordance with changes in the composition of burnt gases or burnt gas constituents to control the supply of fuel or air or both fuel and air.

Other aims and advantages of the invention will appear in the specification, when considered in connection with the accompanying drawing, wherein the figure is a diagrammatic view of one illustrative embodiment of the invention used for regulating or governing combustion in fluid fuel furnaces. Referring particularly to the drawing, a gas furnace is shown to illustrate the invention but said invention is equally applicable to the regulation of the air supply in furnaces using liquid or solid fuel. In this illustrative embodiment of the invention the proportion of gas and combustion air is adjusted in accordance with the content of some constituent or constituents of the burnt or combustion gases, for example with the carbon dioxide content thereof, with the assistance of an electrical governing device. Referring to said figure, the gas conduit 92 is supplied with combustion air through a tube 94, the gas and air mixture thus produced entering the combustion chamber 96 of the furnace. The quantity of combustion air thus supplied is controlled or determined by a throttle valve 98 adjustment of which is effected through a link and lever connection 100, 102 with a piston 104 working in a cylinder 106. Above and below said piston 104, said cylinder is connected by pipes 108, 110 with the interior of a casing 112 through ports 114, 116. Within said casing there is pivoted at 118 for swinging movement in the plane of said two ports, a jet nozzle 120 having its discharge mouth adjacent said ports, said nozzle being supplied with pressure fluid through pipes 122, 124 connected with any suitable source of supply (not shown).

A diaphragm chamber 126 is provided with a diaphragm 128 which is adapted to act upon said nozzle 120 through a link 130 or the like. Pipes 132, 134 leading from said diaphragm chamber 126 at opposite sides of diaphragm 128, connect said diaphragm chamber with the tube 94 at opposite sides of a constriction or orifice plate 136. At the opposite side of the casing 112 there is provided a second diaphragm chamber 138 having a diaphragm 140 acting through a link 142 upon a lever 144 pivoted at 146. It will be noted that said lever 144 and said nozzle 120 extend each in

the general direction of the pivotal point of the other. Between the nozzle 120 and the lever 144 there is provided a contact member 148 adapted to be adjusted longitudinally of said lever and nozzle, said contact member 148 being connected by a link 150 with the piston rod 158 of a piston 160 operating in a cylinder 162 for that purpose. If the contact member 148 be moved toward the pivotal point 146 of said lever 144, the action of the diaphragm 140 upon the nozzle 120 will be increased, said action being decreased upon movement of said contact member 148 in the opposite direction. Pipes 164, 166 connect the diaphragm chamber 138 at opposite sides of said diaphragm 140 with the tube 92 at opposite sides of a constriction or orifice plate 168 within said tube.

It will be seen from the above that said nozzle 120 is subjected to the opposed action of the pressure differentials produced at the orifice plates 136 and 168, said pressure differentials being as is well known proportional to the squares of the amounts of gas or air flowing through the tubes 92 and 94. The throttle valve 98 will therefore be so adjusted that, in proportion to the amount of gas supplied to the combustion chamber 96 through the tube 92, a corresponding amount of combustion air will always be supplied through the tube 94. In order to utilize the combustion gas in the most efficient manner and to the greatest advantage, it is not enough always to maintain the same proportion of combustion air to the proportion of gas supplied. On the contrary this proportion must be varied from time to time as the composition of the combustible gases changes, because different amounts of combustion air will be required corresponding to possible variations in the composition of the combustible gases. In order that combustion may at all times be at the highest point of efficiency, the burnt gases must show a definite composition, and particularly a definite per cent content of certain constituents such as carbon dioxide.

For this purpose there is provided in the illustrative embodiment of the invention a burnt gas tester 170 which delivers an electric current value corresponding to the carbon dioxide content of the burnt gases. Herein said burnt gas tester comprises a plurality of fine wires 172, 174 on the one hand, and 176, 178 on the other hand, which are stretched in cylindrical bores 180, 182, 184, and 186 of two blocks 188, 190. The wires 172 to 178 are connected similarly to a Wheatstone-bridge, receiving current from a battery 192. The bores 180, 182 are filled with atmospheric air while the burnt gases are conducted 55

through the bore 184, 186 by means of a pipe 194 leading to the combustion chamber 86 of the furnace. Before reaching the bores 184, 186 the burnt gases pass through a filter 196 which removes therefrom all dust, soot and other solid matter. The wires 176, 178 which, like the wires 172, 174, are electrically heated by battery 198, are cooled more or less by the burnt gases passing over them according to the carbon dioxide content of said gases.

The bridge current flows over the wires 200, 202 through a coil 66 of a governing device 62 which herein is constructed and operates exactly like that of Fig. 1, and said bridge current varies therefore in accordance with the variation in the carbon dioxide content of the burnt gases. The governing device 62 converts said bridge current into a pressure proportional thereto within a diaphragm chamber 60. This pressure is conveyed through pipe 58 to a regulator, preferably a jet nozzle regulator constructed and operating like that shown in Fig. 1. Said regulator comprises a diaphragm chamber 48 containing a diaphragm 50. The latter acts through a link 52 upon a jet nozzle 38 pivoted at 40 within a casing 36 so as to cause its mouth to swing in the plane of two ports 32 and 34 connected to pipes 204, 206 opening into the cylinder 162 at opposite sides respectively of the piston 160. An adjustable spring 54 acts upon the nozzle 38 in opposition to the action thereon of the diaphragm 50.

From the above it will be apparent that if the composition of the burnt gases changes the bridge current in the conductors 172, 174 will also change as will consequently the pressure within the chamber 60 of the electrical governing device 62. As a result of this the jet nozzle 38 will swing through a corresponding arc and by the consequent movement of the piston 160 the contact member 148 will be moved until by the thus effected change in the proportions of gas and air in the tubes 92, 94 the correct composition of the burnt gases, predetermined by adjustment of the spring 54, shall be restored.

This control by means of or in accordance with the carbon dioxide content of the burnt gases is a corrective control. It is therefore preferable not to allow said control to operate continuously. Accordingly an intermittently operated valve 44 may be employed in either one of the pipes 204, 206 leading to the cylinder 162 for this purpose. This valve 44 would open and close at intervals in a well known manner.

In the example shown there is disclosed the combination of an electrical governing device

with an electrical burnt gas tester which delivers relatively weak electrical current impulses determined by the composition of said burnt gases and which are converted into stronger current values by the electrical governing device and are available for regulating purposes. It will be apparent that in place of the carbon dioxide content measurer herein used, any other electrical burnt gas tester could be used without departing from the spirit of the invention. For example, a burnt gas tester which measures the free oxygen content of the burnt gases may be employed.

It will be apparent to those skilled in the art that the present invention may be embodied in other specific forms without departing from the spirit or essential attributes thereof, and it is therefore desired that the present embodiment of said invention be considered in all respects as illustrative and not restrictive, reference being had to the appended claims rather than to the foregoing description to indicate the scope of the invention.

We claim:

1. Combustion control apparatus for a furnace having conduits for delivering fuel and air comprising, in combination, a valve in at least one of said conduits, a regulator connected to operate said valve in response to the flow of fuel and air in said conduits to control the ratio of fuel and air; a ratio varying member in said regulator; and a combustion tester for the products of combustion from the furnace connected to vary the setting of said ratio varying member and thereby maintain the proper ratio between the fuel and air.

2. Combustion control apparatus for a furnace having conduits for delivering fuel and air comprising, in combination, a valve in one of said conduits; a regulator connected to operate said valve in response to the flow of fuel and air in said conduits to control the ratio of fuel and air; means responsive to the carbon dioxide content of the furnace combustion products to create proportional governing impulses; a governing device connected to be controlled by said means and converting said impulses into proportional fluid pressure impulses; a ratio varying member in said regulator; and means connecting said governor to actuate said ratio varying member in response to said fluid pressure impulses, whereby the carbon dioxide content in the products of combustion is maintained substantially constant.

GUIDO WÜNSCH.

HERBERT ZIEBOLZ. 55
